UNITED STATES PATENT OFFICE.

ARNOLD BINGER, OF NEW YORK, N. Y., ASSIGNOR TO BENJAMIN & EDWARD J. GROSS CO. INC., OF NEW YORK, N. Y., A CORPORATION OF NEW YORK.

DESIGN FOR A JEWELRY-DISPLAY DEVICE.

Application filed July 26, 1926. Serial No. 18,499. Term of patent 3½ years.

To all whom it may concern:

Be it known that I, ARNOLD BINGER, a citizen of the United States, residing at New York city, in the county and State of New York, have invented a new, original, and ornamental Design for a Jewelry-Display Device, of which the following is a specification, reference being had to the accompanying drawing, forming a part thereof.

The figure is a perspective view of a jewelry display device showing my new design.

I claim:

The ornamental design for a jewelry-display device.

In testimony whereof I affix my signature.

ARNOLD BINGER.
